Primary Examiner — Cynthia Underwood*(74) Attorney, Agent, or Firm* — Sughrue Mion, PLLC(57) **CLAIM**

The ornamental design for a double-wall drinking glass, as shown and described.

DESCRIPTION

FIG. 1 is a perspective view of a double-wall drinking glass showing a first embodiment of my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof;

FIG. 7 is a bottom view thereof; and

FIG. 8 is a section view thereof.

FIG. 9 is a perspective view of a double-wall drinking glass showing a second embodiment of my new design;

FIG. 10 is a front elevation view thereof;

FIG. 11 is a rear elevation view thereof;

FIG. 12 is a right side elevation view thereof;

FIG. 13 is a left side elevation view thereof;

FIG. 14 is a top view thereof;

FIG. 15 is a bottom view thereof; and

FIG. 16 is a section view thereof.

FIG. 17 is a perspective view of a double-wall drinking glass showing a third embodiment of my new design;

FIG. 18 is a front elevation view thereof;

FIG. 19 is a rear elevation view thereof;

FIG. 20 is a right side elevation view thereof;

FIG. 21 is a left side elevation view thereof;

FIG. 22 is a top view thereof;

FIG. 23 is a bottom view thereof; and,

FIG. 24 is a section view thereof.
